UNITED STATES PATENT OFFICE.

RICHARD J. SALES, OF DELPHI, INDIANA.

WRENCH.

1,183,497.

Specification of Letters Patent.

Patented May 16, 1916.

Application filed October 15, 1915. Serial No. 56,078.

To all whom it may concern:

Be it known that I, RICHARD J. SALES, a citizen of the United States, residing at Delphi, in the county of Carroll and State 5 of Indiana; have invented new and useful Improvements in Wrenches, of which the following is a specification.

This invention relates to improvements in wrenches and has relation more particularly to that class thereunder known as the 10 slidible jaw type.

The primary object of the invention is the provision of a device of the above stated character wherein means are provided for 15 effecting a speedy adjustment of the movable jaw with respect to the stationary jaw, and for positively holding the movable jaw at the desired point of adjustment and preventing any accidental slipping of the same 20 during the turning action of the wrench.

A still further object of the invention is the provision of a device of the above stated character wherein means are employed for holding the movable jaw in its desired 25 adjusted position and embodying a toothed stationary handle and a pivotally connected toothed handle, and means engaging with the pivotal handle for holding the teeth thereof out of engagement with the teeth of 30 the stationary handle upon inactive position of the wrench.

With the above and other objects in view, the invention consists in the novel features, 35 details of construction and combination of parts which will hereinafter be more fully set forth, illustrated in the accompanying drawings and pointed out in the appended claims.

Figure 1 is a side elevation of the wrench 40 illustrating the handle portions thereof in open position. Fig. 2 is a side elevation of the movable jaw and its parts in dissembled position. Fig. 3 is a side elevation of the stationary jaw and its parts in dissembled 45 position. Fig. 4 is a detail longitudinal section of the stationary handle.

Referring more particularly to the drawing by way of reference characters, 5 denotes my improved wrench comprising a shank 6 provided at its free end with a stationary jaw 1. The free end of the shank 6 has its lower surface for a portion of the shank, beveled upwardly as at 8 in a direction toward the free terminal 9 thereof, the

purpose of which is clearly set forth as the 55 description of the invention is proceeded with. The shank is also provided with an opening 10. Fastened to the free end of the shank is a stationary handle 11 having an inner toothed surface 12. The stationary 60 handle 11 is formed with an elongated opening 13 opening out through the inner end of the handle and having its bottom wall inclined upwardly and rearwardly as at 14 to agree with the inclination of the inclined or 65 beveled portion 8 of the shank, and when the stationary handle is fixedly secured to the shank by means of the threaded pin 14' passing through the registering openings 10 and 16 respectively, the inclined portion 8 70 of the shank tightly binds or wedges against the bevel wall 14² of the opening 13 and thereby obviates the necessity of employing additional fastening means, and furthermore prevents any accidental pivotal movement 75 of the stationary handle 11 during the clamping action of the wrench with a nut or the like to be adjusted.

Mounted for sliding movement upon the shank 6 is a movable jaw 16 having a rearwardly extending reduced shank 17 formed medially of its length with opposed laterally projecting lugs 18, said lugs serving as grips to permit of the jaw 16 being slidably adjusted on the shank 6 as the occasion may 80 demand. The shank 17 has pivotally connected with its free end a movable handle 19, through the medium of a pintle 20, passing through the aperture 21 of the spaced ears 22 and through the opening 23 of said 85 shank. The lower surface of the shank 17 of the movable jaw is inclined upwardly and rearwardly as at 24 for accommodating the attachment to the shank 17, of a leaf spring 25. The leaf spring 25 is attached to the 90 inclined portion 24 of the shank 17 through the medium of a fastening means such as a rivet or the like 26. The spring 25 is of a length greater than the length of the inclined portion 24 to permit a portion thereof to extend beyond the free end 27 of the shank 17, to permit of the spring 25 seating within the recess 28 of the pivotal jaw thereby holding the jaw slightly elevated 95 above the stationary jaw to prevent the 100 teeth thereof from engaging with the teeth of the stationary handle. It will of course be understood, and as is clearly illustrated

the teeth of the pivotal handle are reversed from the slot of the teeth of the stationary handle, whereby when the handles are clamped together, the teeth of the movable handle will fit tightly between the teeth of the stationary handle.

In briefly stating the operation of this invention it is to be stated that the movable jaw is properly adjusted with respect to the fixed jaw by grasping the lugs 18. After this operation, the movable handle 19 is depressed against the action of the spring to force its toothed surface in engagement with the toothed surface of the stationary handle, for preventing any accidental slipping of the wrench upon the article to be turned. Should it be desired however, to positively retain the jaw in a fixed adjustment on the shank 6, such is accomplished by tightening the thumb screw 29.

From the foregoing description, taken in connection with the accompanying drawing, the advantages of construction and of the method of operation will be readily apparent to those skilled in the art to which the invention relates, and while I have described the principles of operation of the device together with the device which I now consider to be the best embodiment thereof, I desire to have it understood that the device shown is merely illustrative and that such advantages may be made when desired as are within the scope of the claims appended hereto.

Copies of this patent may be obtained for five cents each, by addressing the "Commissioner of Patents, Washington, D. C."

Having described my invention, what is claimed is:

1. A wrench comprising a shank having a fixed jaw, a movable jaw slidably mounted on said shank and having a shank portion provided with an upwardly inclined portion, a handle pivotally connected with the inclined portion of the shank of said movable jaw and provided with a recess, and a flat leaf spring secured to the said inclined portion and protruding beyond the terminal thereof, the protruding portion of the spring adapted to engage with the recess of the handle substantially as and for the purpose specified.

2. A wrench comprising a shank having a fixed jaw, a movable jaw slidably mounted upon said shank, a handle pivotally connected with the movable jaw, a handle fixedly secured to the shank of the fixed jaw and provided with an elongated opening, the shank of the fixed jaw having an upwardly beveled portion adapted to engage in the elongated opening of the last mentioned handle, the bottom wall forming the opening being inclined and adapted to be engaged by the beveled portion of the shank of the fixed jaw for the purpose specified.

In testimony whereof I affix my signature in presence of two witnesses.

RICHARD J. SALES.
